UNITED STATES PATENT OFFICE.

BAINBRIDGE W. BURDICK, OF ALBANY, NEW YORK.

DESIGN FOR A PLATE LIFTING-BAR SHELL.

SPECIFICATION forming part of Design No. 31,904, dated November 28, 1899.

Application filed October 25, 1899. Serial No. 734,787. Term of patent 14 years.

To all whom it may concern:

Be it known that I, BAINBRIDGE W. BURDICK, a citizen of the United States, residing at Albany, in the county of Albany and State of New York, have invented and produced a new and original Design for Plate Lifting-Bar Shells, of which the following is a specification, reference being had to the accompanying drawings, forming part thereof.

10 Figure 1 is a perspective view of a plate lifting-bar shell, showing my new design as viewed from its upper side. Fig. 2 is a perspective view of the same viewed from its lower side. Fig. 3 is a section taken transverse to the length of the shell. Fig. 4 is a section taken in direction of the length of the same.

15 As shown in the drawings, the leading and material feature of my design consists in a shell having the shape or configuration shown when viewed as in the several figures. In this shape or configuration of the shell A its upper side wall *a* is shown to be both oblong

and flat in form, and its side walls *b b* are shown to be integral with the upper side wall *a* and connected with the latter by rounded corners *c c* and are inclined inwardly and toward each other as they run downwardly. Its lower side wall portions *d d* are shown to be connected by rounded corners *e e* to the inclined side wall *b b*. The opposite ends of the side walls *b b* are shown to incline inwardly as they run from the ends of the upper wall *a* to the lower wall portions *d d*, and the ends of said lower wall are shown in Fig. 2 to be made with concave form of lines *f*.

Having described my invention, what I claim as new, and desire to secure by Letters Patent, is—

The design for a plate lifting-bar shell, as herein shown and described.

BAINBRIDGE W. BURDICK.
